UNITED STATES PATENT OFFICE.

JOHN N. VALLEY, OF JERSEY CITY, NEW JERSEY.

ELEVATED RAILWAY.

SPECIFICATION forming part of Letters Patent No. 530,810, dated December 11, 1894.

Application filed December 20, 1893. Serial No. 494,158. (No model.)

To all whom it may concern:

Be it known that I, JOHN N. VALLEY, of Jersey City, in the county of Hudson and State of New Jersey, have invented certain new and 5 useful Improvements in Elevated Railways, of which the following is a full, clear, and exact description.

The object of the invention is to provide a strong and durable elevated railway structure, comprising but few elements or parts, and capable of being easily put together, and involving a comparatively low cost.

The invention consists in the novel features hereinafter particularly described and defined in the claims.

Reference is to be had to the accompanying drawings, forming a part of this specification, in which similar letters of reference indicate corresponding parts in all the figures.

Figure 1 is a perspective view of a portion of an elevated railway structure embodying my invention, a car being indicated in dotted lines. Fig. 2 is a broken end view looking in the direction of the arrows, Figs. 3 and 4, parts being in section. Fig. 3 is a broken plan view. Fig. 4 is a broken sectional side elevation; and Fig. 5 is a sectional end view illustrating a slightly different arrangement of the parts.

In constructing an elevated railway in accordance with my invention, I provide suitable posts A, to which suitable transverse girders B are secured by proper devices C. The special construction of said posts, girders 35 and securing devices as shown form no part of the present improvements.

To each girder B, at about the center, a hanger D, is secured, the hangers being substantially of inverted U-shape and the horizontal member d, of which lies flat on the girders while the depending arms d' thereof extend downward below the girder and are secured to the latter by bolts d² or the like.

To the hangers D, vertically disposed angle 45 irons E, are secured, by bolts e passing through one arm or wing of such angle irons and through one arm or member of the hangers, and in like manner, there are secured by bolts e' to the other member or wing of the angle irons, the longitudinally ranging channel beams or stringers F, to which the track rails G, are secured. The meeting ends of

adjacent channel beams are each secured to one depending arm of the same hanger, as will be seen best in Fig. 4, and the hanger thus forms a connection between the channel beams. The adjacent ends of the channel beams are normally spaced, and when changes of temperature cause contraction or expansion of the beams, the depending arms d' of 60 the hangers respond to the movement of the beams.

In Figs. 1 to 4, the channel irons are so secured that their lower flanges f, project from the outside thereof, and the stems g of the 65 T-shaped rails G, rest on the lower flanges f, and are secured thereto by bolts g', or other suitable devices as shown best in Fig. 2, while the upper flanges f', lie against the under side of the transverse girders B. By this construction the T-rails G may be removed and inverted should the upper edge become worn.

It will be seen that the structure above described comprises but few elements, and may be constructed at a comparatively low cost and 75 without the aid of specially skilled workmen.

In the form shown in Fig. 5, the angle irons E', of the form above described, are bolted to separate hangers D', of the inverted U-shape described in connection with the other figures, and the channel bars F' are secured to the said angle irons on the inside of the latter, so that the flanges f, thereof, on which the T rails G' are secured, are disposed toward 80 each other.

The meeting ends of each of the two channel bars F', are connected to the same hanger D', to form an expansion joint as above described.

The structure is designed for any form of 90 car H, either a passenger car, as indicated in Fig. 1, or a freight car, and it is also suitable for transporting logs in lumber regions.

Having thus fully described my invention, I claim as new and desire to secure by Letters 95 Patent—

1. The combination with the supported hangers each having two depending arms, of rail-carrying stringers whose respective meeting ends are each secured to one of the depending arms of the same hanger, substantially as described.

2. In an elevated railway, the combination of suitably supported transverse girders,

- hangers of inverted **U**-shape, secured to said girders, having their depending arms extending below the girders, vertically disposed angle irons secured by one arm or wing to said 5 hangers, longitudinal stringers in the form of channel beams secured to the angle irons, and **T**-rails secured to the flanges of the channel beams, the heads of said rails being disposed vertically, substantially as described.
- 10 3. The herein described elevated railway, comprising suitably supported girders, **U**-shaped hangers secured to said girders, angle irons having one flange or member of each

secured to said hangers, tracks in the form of channel irons which are secured to said angle 15 irons, said tracks being adapted for reversal for bringing the flanges thereof either to the inside or the outside of the structure, and rails secured to said channel irons, the rails consisting of **T** irons having the heads thereof disposed vertically, substantially as described.

JOHN N. VALLEY.
